FLANGE OILER

Angelo Tecca and Patrick Tecca, Livingston,
Mont.

Application August 9, 1938, Serial No. 223,914

2 Claims. (Cl. 184—3)

The present invention relates to improvements in flange oilers for locomotive wheels and has for an object to provide an improved device for economically and efficiently furnishing lubricant in requisite quantities to the flanges of locomotives driving wheels and other wheels in order to reduce wear, to facilitate the movement of the vehicles about curves, and to compensate for the friction due to the lateral movement of locomotives.

Another object of the invention is to provide a device of this character which will function particularly in an automatic manner when the throttle is opened.

A further object of the invention is to provide a device which will cause the oil to be forcibly siphoned from an oil reservoir by steam action, which involves the same steam action that opens the valve which places the device in lubricating communication with the wheel flanges.

Other objects of the invention are to provide a simple arrangement for accomplishing the above described purposes; to so construct the device as to admit of ready accessibility to interior parts for the purpose of cleaning, draining, removal and repair of broken or worn parts; and to lend itself to the proper adjustability of oil deposit.

With the foregoing and other objects in view, the invention will be more fully described hereinafter, and will be more particularly pointed out in the claims appended hereto.

In the drawing, wherein like symbols refer to like or corresponding parts throughout the several views.

Figure 1 is a vertical section, with parts broken away, showing the improved device as applied to the flange of a locomotive wheel, the device being shown in closed position.

Figure 2 is a horizontal section taken on the line 2—2 in Figure 1, and

Figure 3 is a fragmentary vertical section similar to Figure 1 showing the parts in open position.

Referring more particularly to the drawing, 10 designates generally a locomotive driving or other wheel and 11 represents the flange of the wheel which encounters the rail in the normal rotary movement of the wheel for the purpose of maintaining the vehicle on the track.

The oil is fed to the flange by an oil feed rod 12 mounted adjustably and loosely through an oil feed tube 13 which is carried by a Y or other form of coupling 14. The handle of the oil feed rod 12 is designated at 15 and 16 designates a threaded bushing through which the oil feed rod 12 extends whereby the handle 15 lies externally of the device for ease in setting such rod.

The oil is supplied to the Y coupling 14 and oil feed tube 13 through a connection 17 which ex-

tends down from a reducer or valve housing 18. Within the housing is mounted for reciprocation an oil valve 19 having a bevel seat for closing upwardly against a bevel seat 20 formed upon the lower reduced and externally threaded end 21 of a hollow barrel 22. The valve housing 18 may be threaded upon the external threads of the reduced end 21.

The valve 19 may be threaded or otherwise secured upon the lower externally threaded end of 10 the plunger rod or stem 23 and a lock nut 24 serves to hold the valve 19 against displacement from the plunger rod.

The barrel 22 is traversed axially by a bore 25 through which the plunger rod 23 slides vertically or axially; the upper portion of plunger rod 23 having an external diameter substantially the same as the internal diameter of the bore 25 and being fitted substantially to said bore with a tight sliding fit. However, the lower portion of plunger rod 23 is reduced in diameter forming with the bore 25 an annular chamber 26 communicating at all times irrespective of the position of plunger rod 23 with an oil feed duct 27 which opens through barrel 22 into the interior space of the oil reservoir 28. Entrance of oil from reservoir 28 into duct 27 is under the control of a needle valve 29 which passes through a stuffing box 30 and has an exposed end 31 suitable for receiving a crank, wrench, key or the like retained by some authorized person for the purpose of adjusting the needle valve 29 toward and from its seat 32 in the duct 27.

At the upper end of the rod 23 is a plunger 33 traveling in a cylinder 34 and having piston rings 35 and a seat at its lower edge for acting to close against a seat 36 formed in the barrel 22 at the upper end of a large well or socket 37. In the socket is disposed a coil spring 38 acting to normally raise the plunger valve 33 off the seat 36.

The plunger 33 and its plunger rod 23 are traversed from end to end by a passage or bypass 39 placing the chamber above the plunger 33 in direct and open, although restricted, communication at all times with the lower part of 45 the valve housing 18 below the valve 19.

The barrel 22 projects both upwardly and downwardly through the reservoir 28 and may be welded to the reservoir as indicated at 40 and 41 to produce a tight leak-proof fit.

The upper projecting end of the barrel may be externally screw threaded to removably receive the cap 42 through which steam is led by pipe 43 from an appropriate source, for instance from the locomotive valve chest or piston valve.

Oil is supplied to the reservoir 28 through a filling neck 44 having therein a filter screen 45, the neck being ordinarily closed by a closure cap 46 having a breather opening 47 therein. At 48 is shown a drain valve. Cleaning plugs 60

may be inserted in the reservoir wherever necessary.

In operation, when the throttle is turned on or whenever steam is allowed to enter the cap 5 42 it will force down the plunger 33 seating the same against the valve seat 36. In doing so the spring 38 is compressed and the lower oil valve 19 is opened as indicated in Figure 3. The piston rings 35 and the seating of the plunger 10 upon the seat 36 will prevent steam from getting down externally of the plunger and plunger rod. However steam may have a restricted flow downwardly through the passage 39, such steam issuing out of the lower end of the plunger rod 15 and having a siphoning action upon the oil in the reservoir tending to draw this oil out of the reservoir through the duct 27 into chamber 26 and down through the valve housing 18. Here the oil becomes commingled with the steam and 20 atomized by it to some extent. The mixture flows down into the oil feed tube 13 and is deposited by the oil feed rod 12 upon the inside of the flange 11 of the locomotive wheel. As many feed tubes may be connected to valve housing 25 18 as there are wheels on the locomotive or other vehicle.

As soon as the throttle is shut off or the steam pressure above the plunger 33 falls below the value of coil spring 38, such spring will come 30 into action elevating the plunger 33 from its seat 36 and closing the oil valve 19 against its seat 20. This condition of the parts is shown in Figure 1. Therefore neither steam nor oil will flow out the valve housing 18. However 35 the parts are held in readiness for future operation as soon as steam is turned into cap 42. As the oil is withdrawn from reservoir 28 air may enter through the breather opening 41 thus enabling the device to freely function. The 40 amount of oil withdrawn is under the influence of the needle valve 29. Thus the proportion of oil to steam may be nicely regulated.

It will be noted that the oil reservoir 28 surrounds the operating parts of the device through 45 which operating parts the steam passes thus communicating considerable heat and raising the temperature of these parts. The parts being metal have a high conductivity, thereby radiating heat throughout the body of lubricant in 50 the oil reservoir 28. This is important to maintain the oil in a proper condition of fluidity at all times, even in the winter and in cold weather, inasmuch as the faithful performance of the device largely depends upon the liquid 55 condition of the oil.

The seat 36 against which the beveled lower edge of plunger 33 engages acts in a dual capacity; first, these parts act as a stop to limit the downward movement of the plunger and 60 oil valve 19, it being desirable that the oil valve shall not move down far enough for it or its lock nut 24 to engage the lower portion of the mixing housing 16 or to clog the mouth of the pipe connection 17; secondly, these parts form 65 a valve seat sealing the device at 36 to prevent any steam from escaping down upon the outside of the cylinder 34 past the shoulder 36, thereby forcing all of the steam through the passage 39 70 and guaranteeing thereby a constant flow of steam to force the oil from the point 20 through the connection 17 and into the tube 13. In this way all of the oil coming out the chamber

26 will be forced directly onto the flange of the wheel.

It will be further understood that in accordance with the present invention the distribution of oil is evenly regulated. 5

It has been found in some instances during the operation of the device that the needle valve 29 has been tampered with so that the flow of oil through the duct 27 is either too great or too small. Therefore, it is within the spirit 10 of this invention to omit the needle valve 29, leaving the duct 27 of desired size and the stuffing box 30 may either be eliminated or the opening therethrough closed by a suitable plug. In this way the lower valve, 19 and 20, is found sufficient 15 for regulating the flow of oil and steam down through the device.

It is obvious that various changes and modifications may be made in the details of construction and design of the above specifically described embodiment of this invention without departing from the spirit thereof, such changes and modifications being restricted only by the scope of the following claims. 20

What is claimed is:

1. A wheel flange oiler comprising depositing means for the oil upon the flange, a mixing housing for oil and steam in communication with said depositing means, a hollow barrel connected to said housing, an oil reservoir extending about said barrel, a plunger rod movable axially in the hollow barrel, a plunger at the upper portion of said rod, an oil valve at the lower end of said rod, said barrel having a valve seat for said oil valve, means for normally raising said plunger, plunger rod and oil valve, a steam head space above said plunger rod in communication with a source of steam supply, said plunger rod having a steam passage extending therethrough and in open communication with said head space and said housing, said plunger rod having an annular chamber thereabout within the bore of the hollow barrel, said barrel having an oil feed duct in communication with said chamber and with the oil reservoir in all positions of the plunger rod. 35

2. A wheel flange oiler comprising depositing means for the oil upon the flange, a mixing housing connected to said depositing means, a hollow barrel having its lower end connected 50 to said housing and provided with a valve seat, a valve in the housing closing upwardly against said seat, a plunger rod fitted to reciprocate in said hollow barrel and carrying said valve, a chamber about said plunger rod in said barrel, an oil reservoir extending about said barrel and in communication with said chamber, a plunger connected to said plunger rod, a steam head space for said plunger, means for placing said steam head space in communication with a source of steam supply, said plunger rod having a steam passage therethrough placing said steam head space and said housing in restricted but uninterrupted communication, and means biasing said 60 plunger and valve to an upper closed position, said chamber in both the open and closed positions of said valve and plunger rod extending above and below the point of communication between said oil reservoir and chamber whereby 65 the chamber is in open communication with the oil reservoir in all positions of the plunger rod. 70
